UNITED STATES PATENT OFFICE.

JOHN A. TRIMBLE, OF INTERIOR, SOUTH DAKOTA.

NON-REFILLABLE BOTTLE.

SPECIFICATION forming part of Letters Patent No. 606,256, dated June 28, 1898.

Application filed October 18, 1897. Serial No. 655,393. (No model.)

To all whom it may concern:

Be it known that I, JOHN A. TRIMBLE, a citizen of the United States, residing at Interior, in the county of Jackson and State of 5 South Dakota, have invented a certain new and useful Improvement in Non-Refillable Bottles, of which the following is a specification.

My invention relates to a new and useful 10 improvement in non-refillable bottles, and has for its object to provide a simple, cheap, and effective device of this description, which will absolutely preclude the refilling of the bottle and the selling of the contents thereof 15 as the original package by making it necessary to break away a prominent portion of the neck of said bottle, which may carry the trade-mark of the original manufacturer, before the contents of the bottle can be withdrawn.

It is a well-known fact that the goods of 20 certain manufacturers are imitated by the refilling of their bottles after the same have been emptied, thus not only defrauding the manufacturer of his just profits, but also injuring his reputation by the sale of inferior 25 goods under his trade-mark or name. All of this is entirely obviated by my improvement, since it is impossible to withdraw the contents of such a bottle without first breaking 30 away a prominent portion thereof, so that the most casual observer will note the fact that the bottle has been previously used and emptied.

In order that those skilled in the art to 35 which this invention appertains may understand how to make and use the same, the construction and operation will now be described in detail, referring to the accompanying drawing, forming a part of this specification, in which the upper portion of the bottle is shown in vertical section made in accordance with my improvement.

In carrying out my invention as here embodied, A represents the neck of a bottle, 40 which has formed therewith an extension B, projecting downward at an angle and having a passage C formed therein. The top of the neck is closed, as indicated at D, and has a small hole formed therein, through which

passes the rod E, having a head F upon its 50 lower end, while its upper end may be provided with a knob G for its manipulation. One portion of the neck which corresponds to the mouth of the ordinary bottle, as indicated at H, is somewhat smaller than the 55 space I next thereabove, and the passage C is likewise larger than the space H, so that a cork may be easily inserted through the passage C into the space I, with its larger end upward, and this is accomplished when the 60 plunger-rod is in an elevated position, so that the cork may be easily passed sidewise into the space I, after which the downward movement of the plunger-rod will force the cork downward into the space H, which corre- 65 sponds to the mouth of the bottle, thus securely corking the bottle against the outflow of its contents. Of course it will be understood that the bottle is filled previous to these operations, so that when the cork is thus 70 driven home it will be impossible for it to be withdrawn, and therefore the contents of the bottle cannot by any means be extracted therefrom without breaking away a portion of the bottle, and this I provide for by reducing the thickness of the neck upon the line J or by forming a suitable number of holes 75 around this line.

Goods placed in such bottles and sold may be withdrawn by breaking away the upper 80 portion of the neck upon the line J, and this is accomplished by a light blow or otherwise, after which the cork may be easily withdrawn from the mouth of the bottle, the contents of the latter poured therefrom as desired, and 85 the cork used to temporarily close the bottle; but should an attempt be made to refill and reuse the bottle the most casual observer will be made aware of the fact by the absence of the upper and prominent portion of the 90 neck, upon which may be the original manufacturer's trade-mark or name.

Having thus fully described my invention, what I claim as new and useful is—

A bottle having a closed neck, the passage 95 of said neck being enlarged at the top, an extension projecting downwardly and outwardly from said enlarged portion at an acute

angle thereto, said extension having a passage therein of greater diameter than the enlargement of the neck whereby a cork may be inserted in said extension the large end 5 uppermost, passed sidewise into the neck and be pressed downwardly into place, and a plunger-rod run through an opening in the top of the neck, as and for the purpose described.

In testimony whereof I have hereunto affixed my signature in the presence of two sub- 10 scribing witnesses.

JOHN A. TRIMBLE.
